UNITED STATES PATENT OFFICE.

OSCAR WOODWARD, OF BABYLON, NEW YORK, ASSIGNOR TO REMINGTON TYPEWRITER COMPANY, OF ILION, NEW YORK, A CORPORATION OF NEW YORK.

TYPEWRITING-MACHINE.

1,371,591.

Specification of Letters Patent. Patented Mar. 15, 1921.

Application filed July 6, 1920. Serial No. 394,225.

To all whom it may concern:

Be it known that I, OSCAR WOODWARD, citizen of the United States, and resident of Babylon, in the county of Suffolk and State of New York, have invented certain new and useful Improvements in Typewriting-Machines, of which the following is a specification.

My invention relates to typewriting machines and more particularly to tabulating mechanisms therefor.

Heretofore in certain kinds of column selecting mechanisms the constructions were such that any desired column could be selected at will; but where the operator desired merely to use the tabulator to "jump" the carriage to successive columns, or from one column to the next throughout successive fields, it was necessary to operate the selecting keys successively, say, first the number "1" selecting key for the first column, then the number "2" selecting key for the next column, and so on. This entailed on the operator remembering which selecting key was last operated, or an inspection of the work in each instance to determine the position of the next column to be selected, and then a selection and operation of the corresponding or proper tabulator key. This resulted in confusing the operator, diverting the operator's attention from the work in hand, and in loss of time that might have been advantageously used in the production of more work, and sometimes resulted in mistakes which caused further confusion and delay.

The main purpose of the present invention, generally stated, is to provide simple and effective means by which these defects or objections may be overcome and whereby any one of the set of column selecting keys by repeated strokes thereon, or whereby successive strokes on different selecting keys may be used to jump the carriage successively from one column to the next without however destroying the availability of the mechanism to be used for column selecting purposes when desired.

To the above and other ends which will hereinafter appear my invention consists in the features of construction, arrangements of parts and combinations of devices set forth in the following description and particularly pointed out in the appended 55 claims.

In the accompanying drawings, wherein like reference characters designate corresponding parts in the various views,

Figure 1 is a fragmentary side elevation with parts in section of one form of typewriting machine embodying my invention.

Fig. 2 is a detail fragmentary plan view showing the column selecting keys and certain of the connections controlled thereby.

Fig. 3 is an enlarged detail transverse sectional view of the column stop bar and one of the column stops thereon.

Fig. 4 is a detail fragmentary vertical sectional view showing a column stop mounted on the column stop bar and the co-acting column selecting stops, this view illustrating the parts as they appear when the column stops are adjusted to bring the contacts 21 thereon into position where they coact with the projected selecting stops.

Fig. 5 is an enlarged detail transverse sectional view of the parts shown in Fig. 3, the section being taken on the line $\alpha-\alpha$ in said figure and looking in the direction of the arrow at said line.

Fig. 6 is a detail fragmentary rear perspective view of the stop bar and five column stops mounted thereon.

The present invention is in the nature of an improvement on the construction disclosed in my application filed January 3, 1920, Serial No. 349,192, in which certain of the above mentioned results are accomplished. In the said co-pending application the construction disclosed is such that when the parts are set for use in writing in successive columns it is necessary in order to effect such result to actuate always a given one of the column selecting keys, whereas in the present construction an actuation of any one of the series of selecting keys is effective to attain the same result, thus relieving the mind of the operator from the necessity of remembering which key to actuate to effect column to column work, and further avoiding any chance of error by the operator actuating the wrong key.

I have shown my invention in the present instance embodied in a No. 10 Remington machine which includes column selecting mechanism of the character disclosed in the patents to George A. Seib, Nos. 1,132,286 and 1,273,545, dated respectively, March 16, 1915 and July 23, 1918. In such mechanism each selecting stop when coacting with any

given counter or column stop will arrest the carriage at the same letter space position whether the carriage is moved from left to right or from right to left.

5 While the present invention is shown embodied in the No. 10 Remington machine it should be understood that the invention may be incorporated in other styles of typewriting and like machines.

10 I have shown in the drawings only so much of the No. 10 Remington machine as seems necessary to arrive at an understanding of my invention.

15 The frame of the machine includes a top plate 1 on which a carriage 2 is mounted to travel from side to side of the machine, the carriage carrying the usual cylindrical platen 3. Rearwardly projecting arms 4 secured to the carriage near the ends thereof 20 support a column stop bar 5 formed with teeth 6 on opposite sides thereof.

25 Column selecting mechanism of the character shown in the above mentioned Seib patents and similar to that employed in the No. 10 Remington machine is provided to coact with the column stops carried by the column stop bar 5.

30 The tabulator frame 7 is secured by screws 8 to the top plate of the machine and supports pivoted selecting levers 9, each of which terminates at its upper end in a forwardly extending finger 10 which coacts only with its particular pivoted column selecting stop 11. It follows therefore that 35 each column selecting key *a* is operative through the intermediate connections to actuate its companion lever 9 and therethrough to project forwardly the particular selecting stop 11 with which said lever coacts. The 40 selecting stops are arranged one above another in different horizontal planes and each is adapted to swing forwardly on its pivot 11^a in a fixed path or invariable plane which differs from the planes of movement of all 45 of the other stops 11. This is effective ordinarily to bring the projected stop 11 into cooperative relation only with the particular stop projection or arresting face on the particular counter or column stop with which 50 it is to coact. Each of the column or counter stops is designated as a whole by the reference numeral 12. These column stops are constructed somewhat like the column stops disclosed in the application of Elbert S.

55 Dodge, Serial No. 268,252 filed December 26, 1918. Thus each stop is formed with a central body portion 13 bifurcated to receive and straddle the column stop bar. Two sheet metal side plates 14 are riveted at 60 on opposite sides of the body portion 13 of the stop. Each sheet metal plate 14 is likewise bifurcated to straddle a stop bar but the inner parallel walls 14^a of the plates extend inwardly farther than the body portion 65 13 of the stop to enter spaces between

the teeth 6 on the stop bar. Each stop is provided with a finger piece 16 and with a suitable detent to retain the stop against accidental displacement from the bar. In the present instance this detent comprises a ball 70 17, expansion spring 19, and adjusting screw 19^a, all arranged in a socket or aperture 18 formed in the body portion 13 of the stop at the forward edge thereof as the parts appear in Fig. 3. The stops may however be readily detached from the bar and reversed thereon, as shown in Fig. 4, and also adjusted to different points along the bar. 75

Projecting from the body portion of each counter stop 12 at one side thereof is an 80 engaging member or arresting face, projection or contact. These projections or contacts are arranged in different horizontal planes, each having a different path of movement corresponding to the fixed plane 85 of movement of its coacting selecting stop 11. In order that these contacts or projections on the column stops may be clearly distinguished in the drawings I have designated them by separate reference characters, 90 20, 20^a, 20^b, 20^c, 20^d. It will be seen from the foregoing that an operation of the highest selecting stop 11, by its associated 95 selecting key *a*, bearing the index numeral "1," results in moving that selecting stop into the path of travel of the projection 20^d on the right-hand column stop as the parts appear in Fig. 6, said selecting stop 11 being ineffective on all the other column stops. So it is with the other column selecting stops 11, each being coöperative only 100 with the particular column stop (20^c, 20^b, 20^a or 20) with which it is supposed or intended to coact. With this arrangement it is necessary, should the operator desire to 105 move the carriage successively from one column to the next, to operate the selecting keys *a* successively in the one, two, three order, as hereinbefore pointed out.

110 In order to avoid the confusion and errors which may result in using the tabulator to jump the carriage to successive columns in the manner described, I have provided each column stop with an additional stop projection, engaging member, arresting face or contact 21 which as shown in the present instance projects in the opposite direction from the series of stop projections 20, etc., hereinbefore described; or in other words 115 this additional stop 21 is provided on the side opposite the stops 20, etc., and is formed as a part of the body portion 13 of the stop member. These stop projections or contacts 21 are all alike and all have the same path or plane of movement, so that when the column stops are detached and reversed on the stop bar 5 from the Fig. 1 to the Fig. 4 position each of the projections 21 is adapted to coact with each and all of 120 the selecting stops 11. In other words, the 125 130

length of each contact 21 corresponds to the sum of the lengths of all of the stops 20 to 20^a as shown at Fig. 1; and also the length of each contact 21 is slightly greater than 5 the pile or entire series of selecting stops 11 and their interposed guide or division plates 11^a. The path of movement of each contact 21 therefore corresponds to the combined paths of movement of the contacts 20, 20^a, etc., and is vertically disposed and crosses 10 the planes of movement of all of the selecting stops 11. It follows therefore that when the contacts 21 are in operative position each of them will coat with all of the column 15 selecting stops 11. A projection of any of the latter to operative position, therefore, will bring it into coöperation with the contact 21 on the first column stop that reaches it. A repeated operation of any one of the 20 selecting keys *a*, or a successive operation of the different keys *a*, will always result in the carriage being moved successively from one column to the next irrespective of the key or keys actuated. The mind of the operator is therefore not burdened with 25 remembering the order in which the keys must be actuated, or which key was actuated last, or the particular key which must be repeatedly actuated to obtain the desired 30 result, as in prior constructions.

If the column stop bar be fixed to the carriage the column stops may be detached and reversed as pointed out above. However, the column stop bar may be pivoted 35 at one end as at 22 to its supporting member or section 23, which in turn is supported by one of the arms 4 of the carriage. In such construction a locking flange 24 is secured to the stop bar and is provided with two 40 recesses 25 on opposite sides thereof. A locking latch 26 may be pivoted at 27 on the supporting member 23 and have a locking projection 28 at one end thereof which is adapted to be received in either of the 45 recesses 25 in the locking flange and lock the bar against turning movement. A coiled expansion spring 29 interposed between the outer end of the locking latch and the supporting member 23 maintains the latch in 50 its locking position. The opposite end of the stop bar in this construction is pivoted to a supporting member, corresponding to the member 23, in a like manner. By releasing the locking latch 26 and giving the 55 bar a half turn from the position shown in Fig. 6 all of the stop projections 21 will be brought to a position to coat with any selecting stop 11 controlled by the five selecting keys *a*. The advantage of this form of 60 construction is that it is unnecessary to detach the column stops from the bar in order to bring either one set or the other set of stop projections into use.

While I have shown five selecting stops 65 and five coating column stops, it will be

understood that the number of stops employed may be varied.

Various other changes may be made without departing from the scope of my invention.

70

What I claim as new and desire to secure by Letters Patent, is:—

1. In a typewriting machine, the combination of key controlled selecting stops each movable in a single fixed path, and a series 75 of counter-stops provided with two sets of arresting faces, each arresting face of one set coacting with all of the selecting stops, and each arresting face of the other set coacting solely with one of the selecting stops. 80

2. In a typewriting machine, the combination of a series of key controlled selecting stops each movable in an invariable plane, a series of counter-stops provided with two sets of arresting portions, each of 85 the members of one set being arranged for coöperation with all of said selecting stops, the members of the other series being arranged in different planes corresponding to the different planes in which the selecting 90 stops are located and each coacting only with a given one of said selecting stops, and means whereby the engaging members of either series may be brought into position for use. 95

3. In a typewriting machine, the combination of a carriage, and tabulator mechanism for arresting the carriage, said tabulator mechanism including two series of arresting portions, those of one series having different paths of movement one from the other, and each of the arresting portions of the other series having a path of movement which corresponds in extent to the sum of the paths of all of the arresting portions of 105 the first mentioned series. 100

4. In a typewriting machine, the combination of a carriage, and tabulator mechanism for arresting the same, said tabulator mechanism comprising a series of key controlled 110 selecting stops each movable always in a single fixed path which differs from the paths of movement of all of the other selecting stops, a column stop bar, and a series of column stops mounted for individual adjustment to different points along said bar, each column stop having two arresting projections thereon, one series of said arresting projections being variably positioned on the stops so that each will co-act only with a 115 given one of the selecting stops, and the other series being uniformly positioned on the stops so that each projection will coat with all of the selecting stops. 120

5. In a typewriting machine, the combination of a series of key controlled column selecting stops each having a separate and distinct path of movement, and a series of column stops each provided with a contact face of sufficient length to cross the paths of 130

- movement of the entire series of selecting stops, whereby the carriage may be arrested at each successive column irrespective of the keys actuated.
- 5 6. In a typewriting machine, the combination of a series of key controlled column selecting stops each having a separate and distinct path of movement, a series of column stops each provided with a contact face 10 of a length sufficient to contact with one only of said selecting stops, whereby columns may be skipped, and provided also with a second contact face of sufficient length to cross the paths of movement of the entire 15 series of selecting stops whereby the carriage is arrested at each successive column irrespective of the keys actuated, and means which enable either series of stop faces to be brought into use at will.
- 20 7. In a typewriting machine, the combination of a carriage, a series of key controlled selecting stops each movable in a different plane, a column stop bar, and a series of column stops adjustable thereon and each 25 provided with an engaging member that
- travels in a plane which corresponds to the plane of movement of a given one only of said selecting stops, each column stop also provided with an engaging member that crosses the planes of movement of all of the 30 selecting stops so as to coact with each of them.
8. For use in a typewriter tabulating mechanism, a set of column stops each having on one side a short projection which has a different location from all other such projections on the other column stops, and each of said column stops having also on its opposite side an elongated projection equal in length to the combined lengths of all of the 35 short projections of the opposite series.
- Signed at the borough of Manhattan, city of New York, in the county of New York and State of New York this 30th day of June, A. D. 1920.

OSCAR WOODWARD.
